UNITED STATES PATENT OFFICE.

HAROLD GILBERT BROWN, OF WESTMINSTER, ENGLAND, ASSIGNOR TO MCKENZIE, HOLLAND & WESTINGHOUSE POWER SIGNAL COMPANY LIMITED, OF LONDON, ENGLAND.

SIGNALING APPARATUS.

1,233,443.

Specification of Letters Patent. Patented July 17, 1917.

Application filed November 11, 1912. Serial No. 730,559.

To all whom it may concern:

Be it known that I, HAROLD GILBERT BROWN, a citizen of the United States of America, residing at 58 Victoria Street, 5 Westminster, England, have invented new and useful Improvements in Signaling Apparatus, of which the following is a specification.

This invention relates to signaling apparatus of the kind in which the signal indications are controlled by an electric current which is preferably although not exclusively alternating or pulsatory in character, and is more particularly adapted for use 10 with signaling devices comprising two or more lamps preferably of different colors or arranged behind differently colored screens or lenses, the change in the signaling indication being effected by supplying 15 one or the other of the lamps or sets of lamps with electric current derived from any suitable source.

The invention has for its object to provide improved arrangements for the control of 20 signaling apparatus of the above character which shall be more reliable in operation than those hitherto employed and which shall at the same time be simple and cheap to manufacture, install and maintain.

According to the present invention, one 25 or the other of the lamps or other indicating devices of the signaling apparatus, preferably that required to give a "danger" indication, is arranged to be permanently connected in circuit with a source of alternating, pulsatory or continuous current, this 30 circuit also including one circuit of a controlling device, another circuit of which is so related to the first circuit that when supplied 35 with current from the same or some other suitable source the action of the first circuit of the controlling device, as regards permitting current to pass through the other lamp or indicating device of the apparatus, 40 is neutralized or otherwise rendered ineffective. The current traversing the second circuit of the controlling device may also, if desired, be arranged to traverse the other lamp or indicating device of the apparatus 45 so as to give a different signal indication. In cases in which the signaling apparatus is adapted to be operated by alternating or pulsatory currents and to which the present invention is especially applicable, the controlling device may take the form of an in-

ductance device or transformer, one winding of which is permanently connected in circuit with the lamp or other device giving a "danger" indication, the other winding being arranged to be supplied with alternating or pulsatory current which acting inductively upon the portion of the circuit constituted by the first winding either wholly or partly opposes the passage of current therein or diverts current from the lamp circuit through the first winding of the transformer.

In order that the nature of the invention may be clearly understood a preferred form of signaling apparatus embodying the invention as applied to the control of two signaling lamps operated by alternating current, will now be described with reference to the accompanying drawings, of which Figures 1 and 2 are diagrammatic views of different forms of circuit connections.

Referring now to Fig. 1, a signaling lamp adapted to emit a red light so as to give a "danger" indication is indicated at 1, and a similar lamp adapted to emit a green light is indicated at 2. The lamps 1 and 2 are arranged to be supplied with current from the secondary winding 3 of a supply transformer 4, the primary winding 5 of which is connected to any suitable source of alternating current. The red signaling lamp 1 is connected to two suitable points in the transformer winding 3 in series with the secondary winding 6 of a transformer 7 constituting the controlling device of the apparatus. The primary winding 8 of the controlling transformer 7 is connected in series with the green signaling lamp 2 to the terminals of the secondary winding 3 of the transformer 4, this latter circuit also including the contacts 9 of a relay device 10 of any well known type adapted to be operated from a track signaling circuit 11 arranged in the usual manner. The operation of this form of the apparatus is as follows.

When the block section of the track to which the signaling lamps 1 and 2 correspond is not occupied by a vehicle or train, signaling current traversing the track circuit 11 energizes the relay 10 thereby maintaining the switch contacts 9 closed, the presence of a train or vehicle in the block section in question causing the relay 10 to be deenergized and allowing the contacts 9 to open. Under the latter conditions the red

100

105

110

signaling lamp 1 is supplied with current from the portion of the secondary winding 3 of the supply transformer 4 across which it is connected, the circuit through the primary winding 8 of the controlling device 7 being broken at the relay contacts 9. The current supplied from the secondary winding 3 will thus cause the lamp 1 to be illuminated, giving a "danger" signal indication. 5

10 As soon, however, as the train or vehicle has passed out of the block section the relay 10 will be energized so as to close the circuit through the green signaling lamp 2 and the primary winding 8 of the controlling transformer 7. The latter is so designed that under these circumstances the electro-motive force induced in the secondary winding 6, due to the current traversing the primary winding 8, will be equal and opposite to the 15 electro-motive force between those points in the secondary winding 3 of the controlling transformer 4 to which the circuit containing the red signaling lamp 1 is connected. There will thus be impressed on this circuit 20 two equal and opposite electro-motive forces, namely, one due to the transformer 4 and the other due to the controlling transformer 7, so that no current will traverse the secondary winding 6 of the latter, and the red signaling lamp 1 will consequently remain un- 25 illuminated; the green signaling lamp 2 on the other hand being traversed by the current on its own circuit will be illuminated and give a corresponding signal indication. 30

35 Referring now to Fig. 2 which shows a modification of the arrangement above described, the red signaling lamp 1 is in this case connected in parallel with the secondary winding 6 of the controlling transformer 7 between suitable points in the secondary winding 3 of the supply transformer 4, the connections of the green signaling lamp 2 in series with the primary winding 8 of the controlling transformer 7 being the same as 40 in the system illustrated in Fig. 1.

The operation of this form of the invention is as follows.—

So long as the relay 10 is deenergized the circuit of the green signaling lamp 2 will 50 be open and current from the supply transformer 4 will pass through the red signaling lamp 1 and the secondary winding 6 of the controlling transformer 7 in parallel with one another. Owing, however, to the high 55 inductive resistance of the winding 6, the greater portion of the current traversing this circuit will flow through the red signaling lamp 1 which will consequently be illuminated to give a "danger" signal indica- 60 tion.

When the relay 10 is energized to close the circuit through the green signaling lamp 2, the current passing through the circuit of the latter and the primary winding 8 of 65 the controlling transformer 7 will gener-

ate an electro-magnetic flux of such magnitude and phase in the magnetic circuit of the transformer 7, that the effective impedance of the secondary winding 6 will be neutralized, whereupon the current 70 traversing the circuit containing the red signaling lamp 1 will almost entirely traverse the winding 6 of the controlling transformer 7 which thus practically serves to short-circuit the red signaling lamp 1 so 75 that this lamp is not illuminated, the green signaling lamp 2 being illuminated by the current passing through the primary winding 8 to give a corresponding signal- 80 indication.

A resistance 12 may if desired be inserted in the circuit containing the red signaling lamp 1 in order to limit the current in this circuit when the lamp 1 is short circuited by the inductive action of the controlling transformer 7.

The signaling lamps are referred to in the above description as being two in number and as adapted to emit red and green light respectively, but it will be understood 90 that the invention is not limited to the use of two lamps of the colors specified and may be arranged to control two or more sets of lamps or other indicating devices adapted to give any desired signal indica- 95 tion. Furthermore, as will be readily understood, the controlling device 7 which is constituted by an inductive device or transformer in the alternating current systems above described may be replaced by a shunt 100 or other equivalent in cases in which the invention is applied to signaling systems employing continuous or direct currents, the shunt being under these circumstances arranged to divert current from one of the signaling lamps or other indicating devices when a circuit controlled by the track signaling circuit is closed or opened, the sources of supply of continuous current for this purpose being constituted by batteries 110 or otherwise.

Modifications in these and other respects may evidently be made without exceeding the scope of the invention.

I claim as my invention.—

1. In electric signaling apparatus, the combination of an indicating device, a source of voltage therefor permanently connected in circuit with said device, a current-transmitting device also connected to said source and modifying the current traversing said indicating device, and other means for impressing voltage from said source upon said current-transmitting device to vary the action of the latter without interrupting the circuit of the indicating device or that of the current-transmitting device.

2. In an electric signaling apparatus, the combination of a source of current, an indicating device permanently connected to said 130

source, a second indicating device, a circuit of the latter device including said source, means for opening or closing the circuit including the second indicating device and 5 means dependent upon the operation of the second indicating device for controlling the delivery of current to the first mentioned device.

3. In electric signaling apparatus the 10 combination of a plurality of indicating devices, a source of current therefor and a relay for diverting the current from one of said devices to another without interrupting the circuit of the first mentioned device.

15 4. In electric signaling apparatus, the combination of an indicating device, a source of voltage therefor permanently connected in circuit with said device, a current-transmitting device also connected with said 20 source and modifying the current traversing said indicating device, other means for impressing voltage from said source upon said current transmitting device to vary the action of the latter without interrupting the 25 circuit of the indicating device or that of the current-transmitting device, and a second indicating device included in circuit with said means.

5. In electric signaling apparatus, the 30 combination of an indicating device, a source of current therefor permanently connected in circuit with said device, a current-transmitting device also connected with said source and modifying the current traversing 35 said indicating device, a second circuit receiving current from said source and including means for varying the action of said current-transmitting device without interrupting the circuit of the indicating device, 40 and a relay controlling said second circuit.

6. In an electric signaling apparatus the 45 combination of an indicating device, a circuit including said device, a source of current permanently connected in the circuit, a second indicating device and means for delivering operating current to said second indicating device for neutralizing the flow of current through the first device without interrupting the circuit.

7. In an electric signaling apparatus, the 50 combination of a source of alternating current, a signaling device, an operating circuit therefrom including said source, an inductive resistance in said circuit, means electrically connected to said source for 55 varying the resistance introduced into said circuit by said inductive resistance, and a relay for controlling the delivery of operating current to said means for said source.

8. A train signaling apparatus comprising 60 a source of alternating current, a signaling device, a circuit including said source and said device, an inductive resistance in said circuit, a second circuit electrically connected to said source, means included in said 65 second circuit for varying the amount of resistance introduced in the first mentioned circuit by said inductive resistance, a relay for controlling the operation of said means, and a track circuit for controlling the 70 operation of said relay.

9. In electric signaling apparatus the combination with an indicating device, of a source of alternating current permanently 75 connected therewith, a transformer device one winding of which is permanently connected in circuit with said indicating device and a relay for impressing an alternating current voltage upon another winding of the transformer device. 80

10. In an electric signaling apparatus, the combination of an indicating device, a source of alternating current permanently 85 electrically connected thereto, a transformer having one winding electrically connected to said indicating device, a relay for electrically connecting the second winding of the transformer to said source of alternating current, and a second indicating device in circuit with the second winding. 90

In testimony whereof I have signed my name to this specification in the presence of two subscribing witnesses.
